UNITED STATES PATENT OFFICE

151,286

DESIGN FOR AN OXYGEN THERAPY APPARATUS

Andrew H. St. Louis, Utica, N. Y.

Application April 7, 1947, Serial No. 138,213

Term of patent 14 years

(Cl. D83—1)

To all whom it may concern:

Be it known that I, Andrew H. St. Louis, a citizen of the United States, residing at Utica, in the county of Oneida and State of New York, have invented a new, original, and ornamental Design for Oxygen Therapy Apparatus, of which the following is a specification, reference being had to the accompanying drawing, forming part thereof.

In the drawing:

Figure 1 is a view in end elevation of an oxygen therapy apparatus, embodying my new design;

Figure 2 is a view of the apparatus in side elevation; and

Figure 3 is a view of the apparatus in top plan.

I claim:

The ornamental design for an oxygen therapy apparatus, as shown.

ANDREW H. ST. LOUIS.
